Fig.

FIG. 1 is a perspective view of a luggage case showing my new design, the essential feature of which resides in the configuration and appearance of the central panel on the cover portion thereof, it being understood that the opposite side of the luggage case is plain;

FIG. 2 is a top plan view on an enlarged scale with the luggage case omitted for ease of illustration;

FIG. 3 is a side elevational view on an enlarged scale with the luggage case omitted for ease of illustration;

FIG. 4 is an end elevational view on an enlarged scale with the luggage case omitted for ease of illustration.

I claim:

The ornamental design for a luggage case, as shown and described.
